UNITED STATES PATENT OFFICE.

CHARLES R. BIRDSEY, OF HINSDALE, ILLINOIS, ASSIGNOR TO UNITED STATES GYPSUM COMPANY, OF CHICAGO, ILLINOIS, A CORPORATION OF ILLINOIS.

PLASTER BOARD.

Application filed January 3, 1921. Serial No. 434,651.

To all whom it may concern:

Be it known that I, CHARLES R. BIRDSEY, a citizen of the United States, residing at Hinsdale, in the county of Du Page and State of Illinois, have invented certain new and useful Improvements in Plaster Board, of which the following is a description.

My invention belongs to that general class of devices known as plaster board or the like, and relates particularly to an improved board which will be simple, pleasing in appearance, convenient, durable, satisfactory and efficient, and which may be accurately and economically manufactured. The invention relates particularly to a type of board in which the body of plaster, plaster Paris or equivalent plastic material is enclosed on one or both face sides, and is enclosed on one or more edges, the edges conforming to the desired specification as to size and shape. Many other objects and advantages of the construction herein shown and described will be obvious to those skilled in the art from the disclosures herein given. The present invention was described and illustrated in my application Serial No. 348,941, filed January 2, 1920 which matured into Patent 1,358,508 on November 9, 1920.

30 To this end my invention consists in the novel construction, arrangement and combination of parts herein shown and described, and more particularly pointed out in the claims.

35 In the drawings, wherein like reference characters indicate like or corresponding parts,

Fig. 1 is a sectional view of a portion of the plaster board embodying the invention;

Fig. 2 is a perspective view of a portion of the same board; and

Referring to the drawings, first to Figs. 1 and 2, 1 represents a body of suitable material, as for example plaster, plaster Paris, or any equivalent suitable for the purpose, which may be handled in a plastic state and thereafter be allowed to set or harden. The body is enclosed between the covering sheets 2 and 3 of suitable material, and in this connection it may be mentioned that I have found paper of the desired weight and thickness very satisfactory for the purpose.

50 In the type illustrated in Figs. 1 and 3, the two covering sheets are bent or folded

over at opposite edges, it being understood that one or both, or more, edges may be enclosed so as to enclose the plastic material at the edges of the board. Where the board is manufactured by a continuous process and cut into desired lengths, only two opposite edges are enclosed, but this is immaterial as the remaining edges may be enclosed in any suitable manner. As shown, sheet 2 is folded over as at 4, and sheet 3 is folded over as indicated at 5, the edges being brought close together so that they substantially abut. While I have shown the two turned over portions 4 and 5 substantially of the same width, this is, of course, immaterial, as they may be varied in width if so desired.

Ordinarily I prefer to score the sheet as at 6—6 so that the same folds over evenly and gives an even or perfect edge or corners, it being understood that a straight or inclined or other form of edge may be formed, this being a matter of preference.

The covering sheets at the sides and edges are maintained in place, where a body of the type described is used, by the adhering of the covering sheets to the body.

It will be noted that with the construction shown, the edge is substantially completely enclosed, and as before mentioned, the edges may be enclosed at one or both sides, it being immaterial how many edges are so enclosed. Obviously, if the sheets are integral and lapped over one edge, then only the opposite edge would need to be enclosed in the manner described. The resulting product has a straight, smooth, finished edge, at a perfect, desired angle, the board being uniform in width. The completed product has many advantages, including increased strength and durability, and an improved appearance. During shipping and handling, the edges enclosed are protected so that there is no tendency to break away thereat, and there is no sifting out or powdering of the body at the enclosed edges. It will be noted that the construction shown in Fig. 3 is similar to the construction shown in Fig. 3 of the application referred to, except that in this case the imbedded edge is brought to the edge 11 rather than projected inwardly.

Having thus described my invention, it is obvious that various immaterial modifications may be made in the same without de-

parting from the spirit of my invention; hence I do not wish to be understood as limiting myself to the exact form, construction, arrangement and combination of parts herein shown and described, or uses mentioned.

What I claim as new and desire to secure by Letters Patent is:

1. A plaster board of the kind described comprising a body of suitable material, and cover sheets arranged at each side thereof, said sheets folded over the side edges of the board, the extreme edges of said sheets, terminating adjacent each other and the folded over sheet portions on each side edge lying in the plane of that edge.
- 10 2. A plaster board of the kind described comprising a body of suitable material, and

cover sheets arranged at each side thereof, said sheets folded over the side edges of the board, the extreme edges of said sheets abutting each other and the folded over sheet portions on each side edge lying in the plane of that edge.

3. A plaster board of the kind described comprising a body of suitable material, and cover sheets arranged at each side thereof, said sheets folded over the side edges, the extreme edges of said sheets terminating short of each other and the folded over sheet portions on each side edge lying in the plane of that edge.

In testimony whereof, I have hereunto signed my name.

CHARLES R. BIRDSEY.
